CLAIM

The ornamental design for a walkie talkie as shown and described.

DESCRIPTION

FIG. 1 is a top perspective view of a walkie talkie showing my new design;

FIG. 2 is a bottom perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof; and,

FIG. 8 is a bottom plan view thereof.

The evenly broken lines illustrate portions of the walkie talkie that form no part of the claimed design.
